(57) **CLAIM**

The ornamental design for a hat holder, as shown and described.

DESCRIPTION

FIG. 1 is a front perspective view of a hat holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front view thereof shown in use.

The broken lines in the drawings illustrate portions of the hat holder and environmental subject matter, all of which form no part of the claimed design.
